UNITED STATES PATENT OFFICE.

PATRICK J. MONAHAN SULLIVAN, OF WOODCLIFFE-ON-HUDSON, NEW JERSEY,
ASSIGNOR TO MONAHAN ROTARY ENGINE CORPORATION, OF NEW YORK, N. Y.,
A CORPORATION OF NEW YORK.

INTERNAL-COMBUSTION ENGINE.

1,274,811.

Specification of Letters Patent. Patented Aug. 6, 1918.

Application filed February 12, 1917. Serial No. 148,057.

To all whom it may concern:

Be it known that I, PATRICK J. MONAHAN SULLIVAN, a citizen of the United States, and resident of Woodcliff-on-Hudson, in 5 the county of Bergen and State of New Jersey, have invented certain new and useful Improvements in Internal-Combustion Engines, of which the following is a specification.

10 In my prior application, Serial No. 101,011, filed June 1st, 1916, I have disclosed an engine in which the relative axial movement of the cylinder and piston in respect to each other is effected by giving them opposite 15 planetary movements, the movement of one being clockwise and the other counter-clockwise. As there illustrated, the piston and cylinder are carried by identic throw cranks of separate crank shafts geared together for 20 opposite rotation at the same speed. The invention disclosed in said application is generically claimed in my companion applications, Serial Nos. 204,575 and 204,576 filed November 30th, 1917, leaving the more specific claims for the earlier application above referred to.

My present invention relates to an engine of this general type of construction and has for its main object to secure a greater and 30 more uniform application of power without the necessity of using more cranks or crank shafts than are employed in the specific construction illustrated in the application above referred to.

35 Instead of using two separate cranks to support the cylinder and maintain it at all times in parallelism with an initial position and providing a third crank for the piston, I, in my present construction, connect the 40 two cranks to the piston mechanism to hold it in parallelism with the initial position and connect the third crank to the cylinder mechanism. By means of a plurality of piston faces operable within corresponding 45 cylinder portions or chambers, an increased number of power strokes may be produced in respect to the number of crank shaft revolutions. A single double ended cylinder may be provided with a double faced piston 50 therein, or two separate cylinders, rigidly connected and upon opposite sides of the supporting crank shaft, may receive separate pistons, the latter being either rigidly connected or secured to separate crank shafts

geared for rotation at the same speed and 55 in the same direction. For giving a power stroke during each half revolution of the crank shaft, I preferably combine these two possible arrangements and provide two separate double ended cylinders rigidly connected and upon opposite sides of a crank shaft carrying the same and in the two separate cylinders, are separate double-ended pistons mounted for movement together in 60 the same direction which is the opposite direction to that of the movement of the cylinders. 65

By means of this construction, a power stroke may begin at the end of each half crank shaft revolution and therefore a substantially uniform application of power secured even though the engine operate on the four-stroke cycle principle. 70

As all of the movable parts travel along circular paths, it is evident that all jar, 75 shock, or vibration resulting from the sudden stopping and starting of pistons, connecting rods or other parts at the end of a stroke, are eliminated.

As the pistons move in one direction in 80 respect to the center of mass of the engine at the same time the cylinders are moving in the opposite direction in respect to the center of mass, it is evident that by properly proportioning the weight of these parts, a 85 balance is secured which aids in preventing or reducing the transmission of vibration or jar to the frame or base. The bodily movement of the cylinders facilitates their cooling and renders a simple system of radiating fins or flanges efficient and avoids the necessity for the more complicated and expensive water cooling commonly employed with fast running internal combustion engines. 90 95

As the power stroke is produced in one end of one cylinder during the same time that compression is being produced in the opposite end of the other cylinder, it will be evident that the compression operates to 100 cushion the movement resulting from the power stroke and this also aids in securing a desired reduction in strains and jars, and the facilitating of smooth rapid operation. As the cylinders and pistons move in opposite directions, the range of movement of each is only half what it would be were one stationary and the other reciprocating, and 105

therefore the crank shafts may be made lighter, the cranks of only one-quarter the total effective length of a stroke, and the centrifugal force of the parts rotating about 5 fixed centers materially reduced.

As a further important feature of my present construction, I provide a tube mounted on and bodily movable with the cylinders and serving for the delivery of 10 fuel charge to or exhaust gas from the several explosion chambers. The tube has ports in its walls corresponding to ports in the several combustion chambers, and for controlling the flow of gas through said ports, 15 I preferably, as a further important feature of my invention, continuously rotate said tubes so that the ports come into and out of registry at the proper time.

Reference is to be had to the accompanying 20 drawings forming a part of this specification and in which similar reference characters indicate corresponding parts in the two views. In these drawings,

Figure 1 is a central longitudinal section 25 in the plane of the crank shafts, and

Fig. 2 is a central longitudinal section in a plane at right angles thereto.

In the specific construction illustrated, three crank shafts 10, 11, and 12 are mounted 30 in any suitable form of frame or base 13 and in parallel bearings. These three shafts are provided with any suitable form of gearing, whereby the two end shafts 10 and 12 will rotate in the same direction and 35 at the same speed while the center shaft 11 will rotate at the same speed, but in the opposite direction. Merely as an example of such gearing, I have shown three gears 14, 15 and 16, all of the same size and disposed 40 in intermeshing relation in the same plane, one gear being mounted on each shaft. This is merely one example of gearing suitable for the purpose.

The three shafts have cranks 17, 18 and 45 19 of equal throw and the gearing is so meshed that the cranks 17 and 19 of the two end shafts always extend in the same direction from their respective axes and at 180° from the direction in which the crank 18 50 extends. The gearing serves to maintain this relationship of the cranks at all times although to equalize the strain on the two end cranks and to better transmit the load from the end where compression has taken 55 place to the end where the explosion has taken place, the two cranks 17 and 19 may be rigidly connected by links or any other suitable means. As shown, I provide two links 20, each having a bearing at each end 60 and receiving two cranks. These may be off-set intermediate of their ends or the crank 18 may be made shorter than the cranks 17 and 19, or both expedients may be utilized to bring the center portions of the 65 links beyond the ends of the crank 18. The

said center portions may have slots receiving the shaft 11 and permitting of the end-wise and up-and-down movement of the links.

The center link 18 carries two double-ended cylinders 21 and 22 which are held in parallelism by two pistons 23 and 24 disposed therein and mounted on the cranks 17 and 19. The two cylinders have separate working chambers at each end so that there 70 are provided four working chambers 25, 26, 27 and 28, each having its inlet, outlet and ignition means. The pistons have working faces at opposite ends and are preferably substantially counterbalanced on the 75 cranks 17 and 19 which latter extend through slots 29 in the sides of the cylinders. It will of course be evident that the two ends of each cylinder as shown might constitute 80 separate cylinders and the four resulting 85 cylinders rigidly connected in axial alignment to produce the same mechanical effect as the construction illustrated.

Any suitable means may be employed for mounting the cylinders on the crank 18. As 90 shown, a central split block 30 has a bearing encircling the crank 18 and the block itself serves as a cylinder head for each of the cylinders and closes the ends of the two working chambers 26 and 27. 95

It will be noted that the two pistons 23 and 24 move together as though rigidly-connected and that when they move in one direction, the cylinders, which are also rigidly connected, move in the opposite direction. Thus, the centers of mass of the pistons and cylinders move toward and from each other and maintain the center of mass of the engine itself substantially constant. The cylinders may have radiating fins or 105 flanges, whereby they may be cooled and any sort of ignition means, such as spark plugs 31, may be employed for igniting the charges. Even though the cylinders be moving, it is evident that the current may 110 be properly delivered to said spark plugs by the usual flexible wiring.

As the two pistons move together in one direction, while the two cylinders are moving together in the opposite direction, it is 115 evident that the two working chambers 25 and 27 will increase in volume, while the working chambers 26 and 28 are decreasing in volume. By properly timing the supply 120 of the explosive mixture to and the escape of exhaust gas from the cylinders, I may secure an explosion and a corresponding power stroke for each half crank shaft revolution. For instance, with the parts in the position shown in the drawing, the engine 125 may have just completed an intake stroke in the chamber 25, an exhaust stroke in the chamber 26, an explosion stroke in the chamber 27, and a compression stroke in the chamber 28. If this be the case, then the 130

order of firing in the chambers would progress lengthwise of the engine from the chamber 25 to the chamber 28 and for each explosion in the chamber at one side of the 5 crank shaft, there will be a compression in a chamber at the opposite side of the crank shaft, and therefore each explosion is partially cushioned by the accompanying compression.

10 For securing the delivery of explosive mixture to and the escape of exhaust gas from the cylinders, I may provide various means, but I have designed one which constitutes an important feature of my present 15 invention and which is illustrated in the accompanying drawings. In this construction, the pair of cylinders carry two tubes 34 and 35 parallel to said cylinders and of a length substantially equal to the combined 20 length of said cylinders. One tube is mounted above and the other below the cylinders and they are so connected to the cylinders that they are bodily movable therewith. Each cylinder has a port at each 25 end communicating with each tube so that one tube, for instance the upper one 34, may serve to deliver fluid to either end of either cylinder and the exhaust gas from either end of either cylinder may escape to the lower tube 35. Any suitable means for 30 connecting a carburetor or other source of explosive mixture to the tube 34 may be provided and such means forms no portion of my present invention. For instance, 35 a flexible hose, a hollow crank connection, or a sliding telescoping pipe might be employed.

The tube 35 may exhaust direct to the air or may be connected in any suitable manner 40 to a muffler. For controlling the flow of fluid from one tube to the cylinders and from the cylinders to the other tube, I preferably mount the tubes so that they may rotate and provide them with ports which 45 may come into registry with corresponding ports in the cylinders at the proper time during the rotation. As shown, each tube passes through a plurality of casings, bearings or sleeve portions 36, one being disposed 50 adjacent to each end of each cylinder and within these bearings are the ports in the cylinder wall. The tubes 34 and 35 have the different ports so positioned angularly in respect to each other so that one tube can 55 only communicate with one working chamber at a time and will communicate with the four working chambers in succession during a complete rotation of the tube.

In order that the valves may properly operate for a four-cycle engine, each tube is rotated by two-to-one gearing so that for each complete crank shaft rotation, each tube will make one-half a rotation about its own axis. A very simple means for securing this result is a helical gear 37 on the

crank 18 and meshing at all times with two helical gears 38 of twice the size of the gear 37 and rigidly connected to the two tubes 34 and 35 intermediate of their ends. It will be noted that these gears are not merely helical gears, but also have certain functions of a worm gear, as they rotate in planes at right angles to each other. As the tubes and their gears 38 are carried by the cylinders and as the cylinders are carried by the crank 18, it will be evident that the proper intermeshing relationship of the gears will not be disturbed during the bodily movement of the cylinders and cranks.

In order to insure a substantially gas-tight fit of the valve tubes 34 and 35, the latter may have packing rings or sleeves 40 thereon within the bearing parts 36. These sleeves or rings 40 may be removed or replaced in case of wear or may be expandable to properly close the ports.

Having thus described my invention, what I claim as new and desire to secure by Letters Patent is:

1. In combination, three crank-shafts, separate pistons connected to two of said crank shafts and carried thereby, and two rigidly connected cylinders carried by the third crank shaft and receiving said pistons.

2. In combination, three crank shafts, connections whereby all of said crank shafts rotate at the same speed, two in one direction and one in the other, a piston secured to the crank of each of the two crank shafts rotated in the same direction, and two cylinders rigidly connected and carried by the crank of the other crank shaft.

3. In combination, two double-ended cylinders in axial alignment, separate pistons within said cylinders, a crank shaft having its crank connected to said cylinders, and separate crank shafts, each having its crank connected to one of said pistons.

4. In combination, two double-ended cylinders in axial alignment, separate pistons within said cylinders, a crank shaft having its crank connected to said cylinders, separate crank shafts, each having its crank connected to one of said pistons, and gearing insuring the simultaneous and opposite rotation of said crank shafts.

5. In combination, a centrally disposed crank shaft, a plurality of cylinders presenting two separate working chambers on one side of said crank shaft and two separate working chambers on the opposite side of said crank shaft, pistons within said cylinders, and means for bodily moving said pistons in one direction and simultaneously moving said cylinders in the opposite direction.

6. In combination, a pair of rigidly connected double-ended cylinders in axial alignment, a crank shaft having its crank con-

- 4
- nected to and bodily carrying said cylinders, separate pistons in said cylinders, and means for effecting a movement of said pistons in respect to said cylinders during the rotation 5 of said crank shaft.
7. In combination, a pair of parallel crank shafts having cranks of equal throw extending in the same direction, gearing for insuring simultaneous and equal rotation of 10 said crank shafts, pistons bodily carried by said cranks, cylinders receiving said pistons, and means for insuring bodily movement of said cylinders in respect to said pistons during the rotation of said crank shafts.
- 15 8. In combination, a bodily movable, double-ended cylinder having a port at each end thereof, a tube extending lengthwise of said cylinder and bodily carried thereby, said tube having ports registering with the 20 ports of said cylinder, and means for rotating said tube to bring said ports into and out of registry during said bodily movement of said cylinder.
9. In combination, a reciprocating cylinder, having a port, a tube extending lengthwise thereof and having a port registering with the cylinder port, and means for rotating said tube to bring said ports into and 25 out of registry during the reciprocation of 30 said cylinder.
10. In combination, a cylinder, means for imparting to said cylinder a bodily movement in respect to an axis of rotation while retained in parallelism with an initial position, a tube extending lengthwise of said cylinder and serving for the passage therethrough of gas, and means for rotating said tube to control the passage of gas to or from 35 said cylinder.
- 40 11. In combination, three crank shafts disposed parallel and having cranks of equal throw, mechanism for insuring the simultaneous equal movement of two of said crank shafts in one direction and of the other in 45 the opposite direction, piston mechanism connected to said two cranks, and cylinder mechanism connected to said other crank.
12. In combination, two double-ended cylinders in axial alinement and rigidly connected, crank mechanism for giving said cylinders a planetary movement, separate pistons in said cylinders, means for giving one of said pistons a planetary movement in the opposite direction to that of said cylinders, and rigid connections between said 50 pistons.
13. In combination, a cylinder, a piston, a pair of crank shafts, said cylinder being secured to and movable with the crank of one of said shafts, and the piston being secured to and movable with the crank of the other shaft, a rotary valve carried by said cylinder, and gearing for rotating said valve, and including a gear member secured to said valve and a gear member secured to and carried by one of said cranks.
14. In combination, a cylinder, a piston, a crank shaft having its crank secured to said cylinder for bodily moving the cylinder through a circular path during the rotation 70 of the shaft, a rotary valve mounted on said cylinder, a gear secured to said valve, and a gear meshing therewith and carried by the crank of said shaft.
15. In combination, a double-ended cylinder, means for imparting a planetary movement thereto, a double-ended piston within said cylinder, means for imparting thereto a planetary movement in the opposite direction, a rotary valve carried by said cylinder, 75 and gearing for effecting the rotation of said valve by the bodily movement of said cylinder.
16. In combination, a cylinder, a piston, a pair of crank shafts rotatable about parallel 85 spaced axes, one having its crank secured to said cylinder, and the other having its crank secured to said piston, a rotary valve, and gearing connecting said valve and one of said cranks.

Signed at New York, in the county of New York, and State of New York, this 9th day of February, A. D. 1917.

PATRICK J. MONAHAN SULLIVAN.
